US00D809234S

(12) **United States Design Patent** (10) Patent No.: **US D809,234 S**
 Endle et al. (45) Date of Patent: ** Jan. 30, 2018

(54) **NONWOVEN ABRASIVE WITH DOT SURFACE PATTERN**

(71) Applicant: **3M INNOVATIVE PROPERTIES COMPANY**, St. Paul, MN (US)

(72) Inventors: **James P. Endle**, New Richmond, WI (US); **Robert J. Maki**, Hudson, WI (US); **Tien Yi Hsu Whiting**, St. Paul, MN (US); **David C. Raithel**, Hudson, WI (US); **Lauren K. Carlson**, St. Paul, MN (US)

(73) Assignee: **3M Innovative Properties Company**, St. Paul, MN (US)

(**) Term: **15 Years**

(21) Appl. No.: **29/553,968**

(22) Filed: **Feb. 5, 2016**

(51) LOC (11) Cl. **04-01**

(52) U.S. Cl.

USPC **D32/40**

(58) **Field of Classification Search**

USPC D32/40, 35, 39, 41–46, 57; D5/5, 8, 40, D5/35, 39, 56, 57, 58, 60, 61, 62, 53;

(57) **CLAIM**

The ornamental design for a nonwoven abrasive with dot surface pattern, as shown and described.

DESCRIPTION

FIG. 1 is a perspective view of a nonwoven abrasive with dot surface pattern showing the new design;

FIG. 2 is a top view thereof;

FIG. 3 is a bottom view thereof;

FIG. 4 is a front view thereof, the rear view being a mirror image of the front view shown; and,

FIG. 5 is a left side view thereof, the right side view being a mirror image of the left side view shown.

The broken lines which define the bounds of the claimed design form no part thereof.

1 Claim, 2 Drawing Sheets
